UNITED STATES PATENT OFFICE.

HENRY CASE, OF BROOKLYN, NEW YORK, ASSIGNOR TO MARGARET A.
CASE, OF SAME PLACE.

SOUNDING-ROD.

SPECIFICATION forming part of Letters Patent No. 317,089, dated May 5, 1885.

Application filed December 15, 1884. (No model.)

To all whom it may concern:

Be it known that I, HENRY CASE, a citizen of the United States of North America, and a resident of Brooklyn, county of Kings, State 5 of New York, have invented a new and useful Improvement in Sounding-Rods, of which the following is a specification.

The object of this invention is to provide a tubular hydraulic excavating sounding-rod 10 for ascertaining the character of the different strata of earth and the obstructions therein on land and in river or harbor bottoms preparatory to sinking piles or laying foundations for superstructures.

15 The invention consists of a tube, or two or more tubes coupled together, and with a hose, in combination with a jet or stream of water passing through the hose and tube under pressure.

20 Reference is to be had to the accompanying drawings, forming part of the specification, in which similar letters of reference indicate corresponding parts in all the figures.

25 Figure 1 is a side elevation of my improved sounding-rod. Fig. 2 is a sectional side elevation of the same. Fig. 3 shows a modification of the same.

This improved device is constructed of two or more pieces of metal tubing, A B, coupled 30 together by ordinary couplings, C.

The long straight leg of the rod may be composed of one or more sections of tube coupled together, according to the depth at which the soundings are to be made, the lower end or 35 point of the rod being preferably somewhat pointed, as shown at a. The head A of the rod is, preferably, a section of tube bent in U-form, as shown, coupled at one end to the straight leg B, and having coupled to the other 40 end by an ordinary coupling a screw-threaded nipple, D, to the lower end of which a section, E, of hose is secured by a hose-coupling, F. The sounding-rod thus constructed is designed, when in use, to be suspended by a 45 sling, E', as shown in Fig. 1.

In a modified form of this rod, (shown in Fig. 3,) the head consists of a T-shaped tube flanged at one end, as shown at b, and having 50 screwed into the upper end a plug, c, in the center of which an eyebolt, d, is secured, by which the device may be suspended, said eye-

bolt being designed to swivel or turn. The straight leg of the rod is secured to the head by a flanged coupling, f, and bolts f', and the hose is coupled to the horizontal bent arm of 55 the head, as shown.

In operating this device it is usually swung from a derrick or crane, and lowered until the point slightly penetrates the earth. Then water is forced under pressure by a force-pump 60 or other means through the hose and rod and out of the point of the latter. The water is issuing in a stream or jet, as indicated at o, from the orifice in the point of the rod, removes or washes away the earth with which it comes in 65 immediate contact, and the rod, being properly guided, sinks by its own weight in the hole that is excavated by the water-jet, the hole constantly increasing in depth and the rod sinking deeper and deeper as long as the operation continues. As the rod penetrates down through mud, sand, clay, or gravel the characteristics of the various strata are made manifest by the excavated matter. Should the rod encounter an obstruction, the character 70 of the obstruction may be at once determined by applying the hand or ear to the rod and striking the point of the latter upon the obstruction. Contact with stones will give out one sound or character of vibrations, with 75 wood another sound or character of vibrations, and with metal still another, so that each obstructing substance will, in effect, telephone its character through the hollow rod to the operator. If it be desired to remove the 80 obstruction encountered, the point of the sounding-rod can be moved around and beneath it, and the constantly-issuing water-jet 85 will remove the surrounding and sub-lying mud or earth, so that the obstruction will 90 sink in the hole thus made to any desired depth.

The ordinary sounding-rod is simply a sharp-pointed rod of iron that when used must be pushed or driven down by force into 95 the earth. It can be made to penetrate but a short distance into the earth, clay, gravel, or sand, and hence is of but little or no service where piles or deep foundations are to be set, nor will it indicate the character of the various strata through which it may be forced, nor remove obstructions; and the earth-auger 100

that is sometimes applied for these purposes | is but little better than the ordinary rod.

This tubular hydraulic excavating sounding-rod, this combined tube, hose, and water-jet, will also keep open any holes under water or in dry ground, so that anything can be lowered into the hole while open.

Having thus described my invention, I claim as new and desire to secure by Letters Patent—

10 A sounding-rod, constructed substantially as herein shown and described, consisting of a tube, or two or more tubes coupled together,

and with a hose, in combination with a jet or stream of water passing through the hose and tube or tubes under pressure, all arranged 15 and operated as set forth.

In testimony that I claim the foregoing as my invention I have signed my name, in presence of two witnesses, this 9th day of May, 1884.

HENRY CASE.
